UNITED STATES PATENT OFFICE.

FRANK H. WELCH, OF NEW YORK, N. Y.

MUD-GUARD FOR BICYCLES.

SPECIFICATION forming part of Letters Patent No. 655,316, dated August 7, 1900.

Application filed January 11, 1900. Serial No. 1,157. (No model.)

To all whom it may concern:

Be it known that I, FRANK H. WELCH, a citizen of the United States, residing at New York, (Brooklyn,) in the county of Kings and State 5 of New York, have invented certain new and useful Improvements in Mud-Guards for Bicycles, of which the following is a full and complete specification, such as will enable those skilled in the art to which it appertains 10 to make and use the same.

This invention relates to mud-guards for bicycles, and it has specific relation and adaptation to an improved guard which is designed for the main drive-sprocket and 15 chain of the crank-shaft.

One object of my invention is to provide a mud-guard for said drive-sprocket and chain which will be adapted in a special manner for a plurality of adjustments in a lateral plane with respect to the crank-shaft, in a longitudinal plane or direction with respect to the crank-shaft, and in an independent movement with respect to the periphery of the sprocket-wheel, whereby said device may 20 be conveniently applied to and effectively used on various sizes of bicycles and accurately adjusted in position with respect to different diameters of sprocket drive-wheels.

A further object of my invention is to provide 30 an improved device of the specific character just stated which will be very simple and inexpensive and which can be conveniently applied and operated.

In the drawings forming part of this specification, in which like reference characters denote like parts in the several views, Figure 35 1 is a side view showing my improved drive-sprocket and chain mud-guard in operative position with relation to the bicycle-frame 40 and driving mechanism. Fig. 2 is a front end view of the subject-matter illustrated in Fig. 1. Fig. 3 is a detail side view illustrating the variable adjustment of my improved mud-guard device on a plane lateral with respect to the longitudinal plane of the drive-shaft or to and from the latter, and also showing the independent adjustment with 45 respect to the periphery of the sprocket-wheel. Fig. 4 is a detail top or plan view 50 illustrating the adjustment of the device in a plane or direction longitudinal with respect

to the crank-shaft or lateral with respect to the sprocket-gear.

Referring to the drawings, A designates a clamp, which is essentially cylindrical or ring-shaped and which preferably consists of two half members b b, which are secured together at their rear ends by a bolt and nut or set-screw adjusting device, as indicated at c, whereby the ring or clamp A may be secured 60 in adjusted position. The clamp A is adapted to embrace the cylindrical frame-bar, (represented at D,) comprised in the bicycle-frame, which extends forwardly and upwardly from the crank-shaft hanger (represented at e) and 65 at the side of which operates the sprocket drive-gear, (represented at F.) It will be noted that the relative construction and arrangement are such that the cylindrical clamp or ring A is adjustable or slidable longitudinally up and down upon the frame-bar D, that it is also adjustable or turnable in a lateral movement upon said frame-bar, and that it may be tightly bound or secured in any 70 position longitudinally or laterally with respect to the frame-bar D, to which it may be adjusted.

The shield G, which is of usual segmental contour, is carried upon and by the ring or clamp A, the connection being preferably 80 formed by having the frame or arms which carry the shield G in projecting position received between the projecting front ends h of the half members b of the clamp A, the front part of the clamp being adjustably connected by means of a bolt and nut or set-screw adjusting device, as indicated at i, similar to the rear adjustable connection c.

Preferably the frame which sustains the shield G in projecting position consists simply of two divergent arms k k, which are connected at their outer ends to the inner side of the segmental shield G. (See Figs. 2 and 4.) These arms k k extend at an angle downwardly and beyond the plane of the shield G, 95 so that their convergent terminal ends which form the connection with the clamp A are on a plane within the plane occupied by the shield G. Said arms k k may be formed of a single piece of wire bent centrally to form 100 an eye or loop, as represented at l in Figs. 2 and 3, which embraces the securing bolt or

screw at the front end of the clamp device and forms a turning bearing thereon.

From the foregoing description of the general construction and arrangement it will be noted that the shield G is of course carried in both the longitudinal and lateral adjustments of the clamp device A upon the frame-bar D, whereby said shield is adjusted laterally with respect to the sprocket-gear F and also to and from the periphery of the latter, while the turnable connection of the supporting-arms k k with the clamp device A, as just above described, enables an independent swing or adjustment of the shield G, with respect to the periphery of the sprocket-gear F without movement or variation of the position of the main clamp device A.

The shield G occupies a plane away from or beyond the plane of the clamp device A, which is secured to the frame member D, as shown in Figs. 2 and 4, by reason of the inclination or bends of the arms k k, whereby said shield is projected into proper relative position with respect to the sprocket-gear which is at the side of the frame-bar D. When the arms k k are formed of wire, as herein shown and described, they may be readily and conveniently bent, as desired, to enable the perfect adjustment of the shield G with respect to the sprocket-gear under circumstances concerning any specific size or kind of bicycle mechanism or the degree of space which may exist between the sprocket-gear and the frame member D, upon which the clamp device is slidably and adjustably carried. If desired, the inner faces of the front ends h of the half members b of the clamp A may be serrated or roughened, as indicated at m in Fig. 4, to more tightly bind or clamp the eye l, which forms the turnable connection of the arms k with the clamp device. The ring or cylindrical clamp may be interiorly provided with a cushion, as shown at o in Fig. 4, to prevent marring of the surface of the cylindrical frame-bar D. The operation and advantages of my invention will be readily understood.

The device is adapted for convenient and effective application to various sizes of bicycle mechanisms and can be readily adjusted in various directions. The adjustment of the clamp A in a longitudinal direction upon the frame member D will of course carry with it the shield G in such adjustment, while the shield is independently adjustable with relation to the clamp and without movement of the latter. The adjustment of the clamp in a lateral plane with respect to the frame-bar D by simply turning the clamp upon the bar will also carry the shield G in such adjustment. The perfect adaptation of the gear to various sizes of sprocket drive-wheels and in relation to various sizes of frames is thus permitted.

Having fully described my invention, I claim as new and desire to secure by Letters Patent—

1. An improved adjustable mud-guard for the sprocket drive-wheels of bicycles, comprising a cylindrical or ring-shaped clamp adapted to be adjusted laterally and longitudinally upon the cylindrical frame-bar of the bicycle, and a shield having a pivotal connection with said clamp and projecting therefrom on a lateral plane with respect thereto, substantially as and for the purpose set forth. 75

2. An improved mud-guard for the sprocket drive-wheels of bicycles, comprising a cylindrical or ring-shaped clamp adapted to be adjusted longitudinally and laterally upon a cylindrical frame-bar of the bicycle and having half members provided with projecting front ends, a shield carried by arms formed with a loop at their meeting termini, which loop is received between said meeting ends and by which said shield is independently adjustable upon and with relation to the clamp, and an adjusting bolt or screw passing through 85 said meeting ends and loop, substantially as and for the purpose set forth. 90

3. An improved adjustable mud-guard for the sprocket drive-wheels of bicycles, comprising a clamp adapted to be adjusted laterally and longitudinally upon and with respect to the frame-bar of the bicycle, means for securing said clamp in adjusted position, a shield carried upon members projecting outwardly and laterally from one end of said 100 clamp, said shield-carrying member being adjustable upon and with relation to the clamp in a longitudinal plane with respect to the shield device, and means for securing said shield-carrying members in adjusted position 105 with relation to the clamp, substantially as and for the purpose set forth.

4. The combination, with the sprocket drive-wheel and the upwardly and forwardly projecting cylindrical frame-bar D of a bicycle, of a cylindrical clamp or ring surrounding and embracing said frame-bar and adjustable longitudinally and turnable thereon, means for securing said clamp or ring in adjusted position, and a shield carried on a plane 110 beyond and at one side of said clamp or ring and sustained by the latter, said shield having an independent adjustable movement upon and with relation to said ring or clamp in a longitudinal plane with respect to the 115 shield, substantially as shown and described. 120

In testimony that I claim the foregoing as my invention I have signed my name, in presence of the subscribing witnesses, this 8th day of January, 1900.

FRANK H. WELCH.
